FUEL TANK LOCK CAP

Filed March 21, 1929

Inventor
C. M. Rushing.

By A. J. Kennedy, Jr. Attorney

UNITED STATES PATENT OFFICE

CLYDE M. RUSHING, OF BOZEMAN, MONTANA

FUEL-TANK-LOCK CAP

Application filed March 21, 1929. Serial No. 348,937.

This invention relates to a lock cap primarily designed for fuel tanks although is capable of use on tanks or closures generally.

It is aimed to provide an exceedingly simple and inexpensive construction adapted for application to a cap for coaction or engagement with a filling tube or the like engaged by the cap, without necessitating any mutilation or adaptation of the latter to receive the lock.

It is further aimed to provide a novel construction wherein a permutation lock mechanism under key control is carried by the cap and has expandible and retractile means which in the locked position engages frictionally with the inner wall of the filling tube in such manner as to bind one end to straighten in the event the cap should be attempted to be removed by an unauthorized person.

Various additional objects and advantages will become apparent from a consideration of the description following taken in connection with accompanying drawings illustrating an operative embodiment.

In said drawings:—

Figure 1 is a plan view of the cap;

Figure 2 is an inverted plan view of the cap, the filling tube being shown in cross section and the cap as locked;

Figure 3 is a view similar to Figure 2 in which the cap is shown unlocked;

Figure 4 is a central vertical sectional view taken on the line 4—4 of Figure 2; and

Figure 5 is a central vertical sectional view taken on the line 5—5 of Figure 2.

Figure 6 is an enlarged view showing a connection in the operating mechanism of the device.

Referring specifically to the drawings, 10 designates the filling tube, nipple or the like of a gasoline tank as used on automobiles or other equivalent tube to which a cap 11 of conventional structure is screw threaded as at 12.

In accordance with my invention, a conventional lock generally designated 13 is carried by the cap 11 and is under control of a key at 14, the specific construction of

present invention. The rotatable cylinder of the lock is shown at 15 and its housing 16 is rigidly fastened to the cap 11.

Rotatable with the drum 15 is a plate 17 which is maintained in place on the drum 55 by a disk 18 screwed thereto as at 19.

The housing or fixed part 16 has spaced apart ears 18' between which the inner ends of lock members 20 are positioned and pivotally mounted on removable screws 21. In 60 the locked position, as shown in Figure 2, the lock members 20 are adapted to frictionally engage the inner wall of the tube 10 and they are urged to that position by means of expansive springs 22 which surround arcuate rods 23 pivoted at 24' to the lock members. The rods 23 pass through guide lugs 24' rising from arms 25 of the plate 17 and beyond such lugs 24' have heads 26 thereon. 65

In the locked position of the parts, a stop lug 27 on one of the arms 25 abuts the casting 16 at a part 28 thereof and such engagement is maintained through the expansion of the springs 22. In the said locked position, it will be realized that any attempt to unscrew the cap will simply result in tending to straighten or move the lock members 20 to a truly radial position, which of course cannot be done in view of their length and the fact that they bind with the inner wall of tube 10 when tangential. At the same time, upon insertion of the proper key 14, the cylinder 15 may be slightly turned so that the plate 17 will be rocked, thereby pulling the rods 23 and the lock members 20 to the unlocked position shown in Figure 3. In the position of Figure 3, the cap can be readily removed. The cap may be replaced when the lugs are either in locked or unlocked position since the latter yield during movement toward the locking position but will not permit retrograde movement of the cap. 85

Various changes may be resorted to provided they fall within the spirit and scope 90 of the invention.

I claim as my invention—

1. A cap having a lock controlled plate concentric with the cap, a lock member carried by the cap, and a spring and rod connection between the lock member and plate 100

normally urging the member to locked position.

2. A cap of the class described having a key-controlled plate, a lock member pivoted to the cap and adapted to wedge between the cap and the element to which it is fastened, means whereby the operation of the plate may retract said wedge member comprising an arcuate rod connected to the wedge member, means on the plate through which the rod loosely passes, a fastening on the rod engaged by the latter means, and an expansive spring on the rod between the latter means and the lock member.
15. 3. A cap of the class described having a key-controlled plate, a lock member pivoted to the cap and adapted to wedge between the cap and the element to which it is fastened, means whereby the operation of the plate may retract said wedge member comprising an arcuate rod connected to the wedge member, means on the plate through which the rod loosely passes, a fastening on the rod engaged by the latter means, an expansive spring on the rod between the latter means and the lock member, and a fixed element on the cap and a cooperating stop on the plate normally maintained in engagement by said spring means.
30. In testimony whereof I affix my signature.
CLYDE M. RUSHING.
